UNITED STATES PATENT OFFICE.

JOHN LEE, OF STERLING, OHIO.

WRENCH.

SPECIFICATION forming part of Letters Patent No. 288,713, dated November 20, 1883.

Application filed August 23, 1883. (No model.)

To all whom it may concern:

Be it known that I, JOHN LEE, a citizen of the United States, residing at Sterling, in the county of Wayne and State of Ohio, have invented a new and useful Wrench, of which the following is a specification, reference being had to the accompanying drawings.

This invention relates to that class of wrenches which are provided with a sliding jaw; and it consists in certain improvements in the construction of the same, having for their object to produce a device which shall possess superior advantages in point of simplicity, durability, inexpensiveness, and general efficiency, as will be hereinafter fully described, and particularly pointed out in the claims.

In the drawings hereto annexed, Figure 1 is a side view of a wrench embodying my improvements. Fig. 2 is a vertical longitudinal sectional view of the same; and Fig. 3 is a section on line *x x*, Fig. 2.

The same letters refer to the same parts in all the figures.

In the drawings, A designates the shank of the wrench; B, the fixed jaw at the end of the same, and C the handle. The side of the shank is provided with teeth D.

E is the movable jaw, which is mounted and slides upon the shank A. The jaw E is provided with two laterally-projecting straps or brackets, *a a'*, to which is secured a bar, F, provided with teeth G, which engage the teeth D of the shank A. The inner side of the jaw E has a tapering recess, H, in which is fitted a wedge, I, having a stem, J, that projects below the jaw E.

Swiveled upon the lower end of the jaw E is a cylindrical burr, K, having a spiral groove, L, engaging a flange or stud, M, upon the stem J of the wedge. The said stem is also provided

with flanges N, overlapping the sides of the shank A and the burr K, and which serve to guide the wedge when operated. The burr K is provided with a thumb-piece, O, by means of which it may be easily turned.

The operation will be easily understood. By turning the burr in one direction the wedge is lowered, thus enabling the movable jaw to be moved upon the shank. By turning the burr in the opposite direction the wedge is raised and the jaw tightened, and held securely upon the shank in the position to which it may have been adjusted.

I claim as my invention and desire to secure by Letters Patent of the United States—

1. In a wrench, the combination of the shank, the movable jaw having an interior beveled recess, a wedge fitted in said recess adjoining the shank, and having a stem extending below the jaw, and a burr mounted upon the lower end of said jaw and engaging a flange upon the said stem, substantially as set forth.

2. In a wrench, the combination of the shank, the movable jaw having an interior beveled recess, a wedge fitted in said recess adjoining the shank, and having a stem extending below the jaw, flanges projecting from said stem at the sides of the shank, and a burr swiveled upon the lower end of the jaw, and having a suitable thumb-piece and a spiral flange engaging a stud upon the stem of the wedge, substantially as set forth.

In testimony that I claim the foregoing as my own I have hereto affixed my signature in presence of two witnesses.

JOHN LEE.
